CLAIM

The ornamental design for a double-sided three-tier bulk food display stand, as shown and described.

DESCRIPTION

FIG. 1 is a front elevation view of a double-sided three-tier bulk food display stand, the view from the back being identical;

FIG. 2 is a perspective view on a reduced scale;

FIG. 3 is a bottom plan view of FIG. 1;

FIG. 4 is a top plan view of FIG. 1; and,

FIG. 5 is a side elevation view, the view from the opposite side being a mirror image.
